UNITED STATES PATENT OFFICE.

JOHN F. FORD AND JOHN J. TATUM, OF BALTIMORE, MARYLAND.

METHOD OF RECLAIMING AND MEANS FOR REENFORCING CAST SIDE FRAMES FOR CAR TRUCKS.

Application filed July 3, 1923. Serial No. 649,264.

To all whom it may concern:

Be it known that we, JOHN F. FORD and JOHN J. TATUM, citizens of the United States, residing at Baltimore, in the State 5 of Maryland, have invented certain new and useful Improvements in Methods of Reclaiming and Means for Reenforcing Cast Side Frames for Car Trucks; and we do hereby declare the following to be a full, 10 clear, and exact description of the invention, such as will enable others skilled in the art to which it appertains to make and use the same.

Our invention relates to a method of reclaiming and means for re-enforcing cast side frames for car trucks.

Cast side frames are largely used for railway car trucks both in the building of new trucks and in the replacement of side frames 20 of other types when the trucks are being repaired.

The cast side frames, which are usually formed of steel, but may be of any suitable material, sometimes fail in service by cracking, 25 which cracks are principally due to the metal being honey-combed in structure or to an incipient crack which forms when the metal of the frame is cooling after being cast. Heretofore when cracking occurred, 30 side frames of this type have been repaired by the process of autogenously welding the parts together. In practice it has been found very difficult to insure uniformity of the welds owing to the fact that the metal used in the welding process was not of uniformly high quality and also to the fact 35 there might be a honey-combed structure of the metal each side of the crack, and as a consequence, the side frames frequently failed after repairing. The failure of a side 40 frame of a car truck causes considerable damage.

Among the objects of our invention are:—

To provide a method for reclaiming de- 45 formed or fractured cast side frames of car trucks, which consists in removing the deformation or autogenously welding the cracks as the case may be and then applying 50 to the side member a bottom arch bar which, in itself, may be sufficiently strong to stand 55 all the stresses applied to the side frames by the axle boxes and king pin or which may have any approved capacity for resisting stresses, but whatever the strength of the bottom arch bar its strength is additive to

the strength of the side frame after repair so as to greatly increase the factor of safety.

To provide a means for re-enforcing cast side frames for car trucks so as to insure that deformation or a fracture of the same 60 will not occur even though the material of said side frame be defective.

In carrying out our invention, we proceed according to the method set forth in the following specification and use the instrumentalities shown in the accompanying drawings, in which:—

Figure 1 is a view of a side frame of a car truck which has been reclaimed by our improved method and has our improved re-enforcing means applied thereto.

Fig. 2 is a section along the line 2—2 in Fig. 1 looking in the direction of the arrows.

Fig. 3 is a section similar to Fig. 2 but showing a re-enforcing means that is formed 75 of a channel bar.

Fig. 4 is a section similar to Fig. 2 but showing a re-enforcing means that is formed of an angle bar.

In the drawings:—

5 represents a cast side frame for a car truck. The metal that is employed is usually of steel and at times there are shrinkage cracks therein which occur when the side frame is cooling after being cast. 85 Other defects in the material are honey-combed portions which have a strength greatly below what they would have if they were formed of sound metal. Side frames having these defects fail in practice and it becomes necessary to repair or reclaim the same.

In carrying out our method for reclaiming damaged side frames, we put in proper shape any parts that may be deformed by bending or twisting and repair by an autogenous or other weld any cracks or fractures that may exist. We then remove the under surfaces 6, 7, 8, 9 and 10 of the side frame any projections that may exist thereon and fit to said surfaces our re-enforcing means or bottom arch bar 11 which is preferably composed of a rolled bar having a high tensile strength. The bar 11 is to be provided with holes for the reception of the bolts 12 which secure the axle boxes 13 to the side frame 5. The axle boxes 13—13 may be tied together by the brace bar 14 secured thereto by the bolts 12, if desired.

The bar 11 is rectangular in section, but 110

it may be made a channel in cross section such as is shown at 15 in Fig. 3, or it may be angular in cross section as shown at 16 in Fig. 4.

5. Our re-enforcing means such as 11, 15 and 16 may be applied to new side frames 5, if desired.

Thus it will be seen that our invention resides in a method of reclaiming side frames 10 of car trucks which includes a provision of a re-enforcing means for side frames so that even if there are defects in the material of the latter after reclamation, the joint strength of the side frame and our re-enforcing means will be sufficiently great to 15 resist all stresses to which they may be subjected.

It is to be noted that while we have shown our improved method as comprehending the 20 attachment of an arch bar to the bottom surface of a cast metal frame, yet it is to be understood that this is for purposes of illustration only, for the arch bar which we have shown as fitted to the bottom surface 25 is merely a representative of any form of reinforcement that might, in itself, sustain all or part of the stresses applied to the cast side frame whether such reinforcement be applied to the bottom surface of the side 30 frame or any other part thereof.

We claim:—

1. The herein described method of reclaiming damaged cast side frames for car trucks which consists in repairing the damage 35 and then applying an arch bar to the bottom of said frame.

2. The herein described method of reclaiming damaged cast side frames for car

trucks which consists in repairing the damage and then applying an arch bar to the 40 bottom of said frame, said bar having sufficient strength to resist the normal stresses applied to said frame.

3. The herein described method of reclaiming cracked cast side frames for car 45 trucks which consists in welding together the ends at the crack and then applying a bottom arch bar to said frame.

4. The herein described method of reclaiming deformed cast side frames for car 50 trucks which consists in reforming said frame and then applying an arch bar to the bottom of said frame.

5. The herein described method of reclaiming damaged cast side frames for car 55 trucks which consists in repairing the damage, removing projections from the bottom surfaces of said frame, and then applying an arch bar to the bottom of said surfaces.

6. In a car truck the combination of a 60 cast side frame and a reenforcement consisting of a rolled metal arch bar fitted to the bottom surfaces of said frame.

7. In a car truck the combination of a 65 cast side frame and a reenforcement consisting of a rolled metal arch bar fitted to said frame.

8. The herein described method of reclaiming damaged cast side frames for car 70 trucks which consists in repairing the damage and then applying a rolled metal reenforcement to said frame.

In testimony whereof, we affix our signature.

JOHN F. FORD.
JOHN J. TATUM.
